UNITED STATES PATENT OFFICE.

BENJAMIN SCARLES, OF STOCKTON, CALIFORNIA, ASSIGNOR TO PACIFIC STEEL & WIRE COMPANY, OF SAN FRANCISCO, CALIFORNIA, A CORPORATION OF CALIFORNIA.

WIRE FABRIC.

SPECIFICATION forming part of Letters Patent No. 784,892, dated March 14, 1905.

Application filed October 19, 1903. Serial No. 177,555.

To all whom it may concern:

Be it known that I, BENJAMIN SCARLES, a citizen of the United States, residing at Stockton, in the county of San Joaquin, State of California, have invented certain new and useful Improvements in Wire Fabric; and I do hereby declare the following to be a full, clear, and exact description of the same.

The hereinafter-described wire fabric or netting is of that class known as "fence" fabric or netting used for the construction of farm or range fencing, although equally as well adapted for gates, tree-boxes, metallic bond for cement-work, or any other purpose desired of this class of material, the object of the invention being to materially increase the strength of the fabric without increasing the cost of its manufacture.

To comprehend the invention, reference should be had to the accompanying sheet of drawings, wherein—

Figure 1 is a detail broken view disclosing a portion of the improved wire fabric or netting. Fig. 2 is a detail enlarged view of one of the joints of the mesh or stay wires with the longitudinal wires, one end of said joint being unwoven or the strands separated. Fig. 3 is a cross-sectional end view on line 3 3, Fig. 2, of the drawings. Fig. 4 is a similar view taken on line 4 4 of said view.

Referring to Figs. 1, 2, and 4 of the drawings, the numeral 1 indicates the longitudinal wires of the fabric, and 5 7 the mesh or stay wires. The said mesh or stay wires are run diagonally of the longitudinal wires, being united thereto and to each other by the joint 8. The formation of this joint corresponds to the section of a cable—that is, it is formed without a hollow center. To successfully construct such joint, the longitudinal wires as fed through the machine are twisted upon their own axes, so that as the mesh or stay wires are twisted onto the said longitudinal wires they will lie within the depressions 9 of such wires in the same manner as the strands of a cable wind onto each other. A solid joint is thus formed in contradistinction to what is known as a "coil-joint," which corre-

sponds to the formation of a joint constructed upon a mandrel or inner core, the removal of which core leaves a hollow center.

Where the longitudinal wires are twisted on their axes, the wire is materially strengthened, as greater stiffness and rigidity results at the joints formed by the mesh-wires and to the longitudinal wires intermediate the said joints.

In the drawings a standard size weave or mesh is disclosed of hexagon shape; but it is obvious that the size and shape of the mesh may be varied in accordance with the desire of the manufacturer of the fabric or netting.

The essential feature of the present invention resides in twisting each longitudinal wire on its own axis to give strength and rigidity thereto, so that when the mesh or stay wires are united thereto a solid or cable-wound joint is formed.

In carrying out my invention I provide upper and lower longitudinal wires and an intermediate or series of intermediate longitudinal wires, (indicated by the reference-numeral 1,) said wires being twisted upon their vertical axes to form a series of closely-wound coils throughout their length. To said longitudinal wires are intertwined for a given length mesh or stay wires 5, 7, and 10 to form the closed joints 8, the said stay-wires 5, 7, and 10 at the ends of said joints projecting diagonally at opposite angles and intertwined, as before, with the adjacent longitudinal wires, and so on during the construction of the fiber.

Having thus described the invention, what is claimed as new, and desired to be protected by Letters Patent, is—

1. A wire fabric or netting, comprising upper and lower longitudinal wires, an intermediate longitudinal wire formed with a series of closely-wound coils throughout its length, and diagonally-disposed stay-wires extending inwardly from said upper and lower longitudinal wires and intertwined with the coils of said intermediate wire, forming closed joints.

2. A wire fabric or netting, comprising upper and lower longitudinal wires, an interme-

diate longitudinal wire formed with a series of closely-wound coils throughout its length, and diagonally-disposed stay-wires extending inwardly from said upper and lower longitudinal wires, adjacent stay-wires being inter-twisted with the coils of said intermediate wire forming closed joints.

In witness whereof I have hereunto set my hand.

BENJAMIN SCARLES.
